CLAIM

The ornamental design for a fishline guide tube for an internal fishline type fishing rod, as shown.

DESCRIPTION

FIG. 1 is a perspective view as seen from the left-hand side of the fishline guide tube for an internal fishline type fishing rod of the present invention;

FIG. 2 is a front elevational view thereof;

FIG. 3 is an end view from the reel end thereof;

FIG. 4 is an end view from the distal end thereof;

FIG. 5 is a top plan view thereof;

FIG. 6 is a bottom view thereof; and,

FIG. 7 is the opposite side perspective view of FIG. 1, the broken line showing of environment being for illustrative purposes only and forming no part of claimed design.
